(57) **CLAIM**

The ornamental design for a display fixture component, as shown and described.

DESCRIPTION

FIG. 1 is a perspective view of a display fixture component showing my new design;

FIG. 2 is a front elevational view, the rear elevational view being a mirror image thereof;

FIG. 3 is a right side elevational view, the left side elevational view being a mirror image thereof;

FIG. 4 is a top plan view; and,

FIG. 5 is a bottom plan view.

The broken lines shown in the drawings are for illustration purpose only and form no part of the claimed design.
